METHOD FOR CARRYING OUT ENDOOTHERMIC GAS REACTIONS IN REGENERATIVE GAS HEATERS

Heinrich Koppers, Friedrich Totzek, and Willy Linder, Essen, Germany, assignors, by mesne assignments, to Koppers Company, Pittsburgh, Pa., a corporation of Delaware

Application February 6, 1939, Serial No. 254,916
In Germany February 7, 1938

3 Claims. (Cl. 48—214)

The present invention relates to the carrying out of endothermic gas reactions at high temperatures, for instance the reaction of methane or methane containing gases with steam in forming carbon monoxide and hydrogen, or similar endothermic processes, where the gas or the gas-steam mixture is heated up, in one operating period, to the reaction temperature in regenerative gas heaters, and the checkerwork of the gas heaters is re-heated, in another period, by hot combustion gases flowing in direction counter current to the gas or gas-steam mixture to be converted.

When carrying out such endothermic reactions it was found that the temperature of the waste gases, which are to be extracted at the lower end by means of a normal cast iron grate, rises more towards the end of the re-heating period. After a certain time of the heating period has elapsed the temperature of the waste gases becomes so high that the cast iron grate of the gas heater is dangerously superheated.

In order to eliminate such deficiencies when performing such endothermic gas reactions, which take place at high temperatures in regenerative gas heaters, the invention provides for heating up the checker work of the gas heater, during the heating period, in the reaction zone on one hand and in the preheating zone on the other hand by means of varying adjustable quantities of heating gases so that the checker work is charged with that quantity of heat in the two zones which corresponds to the heat required in each of said two checker work zones.

Preferably the invention is practically carried out in such a way that an adjustable part of the hot heating gases from the gas heater is drawn off from the checker work at a point of increased temperature while the rest of the heating gases passes in the usual way along to the preheating zone up to the grate of the gas heater from where it escapes through the normal waste gas flue.

Another feature of the invention consists in gradually increasing the quantity of the hot heating gases that is branched-off from the gas heater during each heating period.

We will give now a detailed explanation of our invention.

It may be assumed that the checker work of a regenerative gas heater is heated up in such a way as is usual for instance with the hot blast stove of the system Cowper. In this case the temperature of the checker work shows practically a straight rise. The discordances from

the straight rise in temperature are only due to differences in the specific heat and the thermal conductivity of the material at various temperatures. If a mixture of methane and steam is led in counter current through such a heat charged gas heater, i. e. with a vertical gas heater in the direction from the bottom to the top, a certain heat quantity is absorbed from the lower part of the gas heater in order to heat up the gas-steam mixture to the reaction temperature. The quantity of heat absorbed in this temperature zone of the checker work of the well known hot blast stove corresponds substantially to the heat absorption by the zone. In other words, such a quantity of heat is drawn off from the checker work in the lower zone of the checker work, also called the preheating zone, as results from the specific heat of the gases and steam to be heated. This heat quantity practically equals the heat quantity which the heating gases are able to give-off to the checker work in heating-up the preheating zone.

As soon as the preheated gas-steam mixture has reached such a temperature as is necessary for the reaction, the heat required for the maintenance of the reaction is drawn-off from the checker work. Furthermore a certain heat quantity is still further taken off from the checker work in the reaction zone in order to heat up the gas and gas-steam mixture and the reaction products, respectively, to a higher temperature so that the reaction may be carried out as completely as possible.

The total quantity of the heat drawn off from the checker work in the reaction zone of the gas heater is considerably higher than the heat quantity which is needed for the normal heating up of non-reacting gases for instance for the hot blast in the known blast stove. The drop in temperature of the checker work during the reaction period in the reaction zone is considerably higher than in the corresponding zone of a hot blast stove. The checker work must therefore be charged with a greater quantity of heat in the reaction zone. This involves a corresponding increase in the volume of the heating gas.

If the gas heater is heated up by leading an increased quantity of hot combustion gases from the top to the bottom of a vertical gas heater through the checker work much heat will be absorbed at first in the reaction zone owing to the great difference in temperature between the checker work and the heating media. Therefore the temperature of the waste gas will be low at the beginning of the heating period correspond-

ing to the temperature of the gases to be treated, at the inlet of the gas heater.

But after a comparatively short time the waste gas temperature rises considerably and reaches gradually a maximum which is much higher than the maximum waste gas temperature which could be observed in the heating period of a well constructed hot blast stove. The reason for this fact is that the volume of the heating gases coming from the reaction zone is too large for the heating of the preheating zone where less heat is absorbed. From this it results that a very great rise in the temperature of the waste gases takes place during the heating period.

If one draws off hot heating gases from the Cowper, for instance from a point between the preheating zone and reaction zone, according to the invention it is possible to control the heat quantities which are supplied by the heating gases in the preheating zone in such a way that the highest temperature of waste gases permissible for the cast iron grate can be easily observed. The hot heating gases removed from the Cowper stove may be advantageously used for the production of steam which is required for the reaction of the methane containing gas or the like. It is also possible to use the hot heating gases for the preheating of the combustion air or for the heating of other media.

It may be assumed that for the practice of the invention a vertical regenerative gas heater of the type of hot blast stove of the system "Cowper" is made use of, wherein a methane containing gas is to react with steam at high temperatures. The gas to be heated up may enter the gas heater, at the bottom, with a temperature of 120 degrees centigrade. The maximum temperature which the gas-steam mixture and reaction gas, respectively, shall reach in order to make the reaction as complete as possible may be 1250° C. at the beginning and 1150° C. at the end of the reaction period. This difference in temperature is due to the drop in temperature of the refractory chequer work which serves as heat transmitter. As soon as the temperature of the reaction products has arrived at 1150° C. the regenerative system is reversed and the chequer work of the gas heater is heated up again. This is performed in such a manner that hot combustion gases are led from the top to the bottom of the gas heater. The temperature of the combustion gases entering the chequer work may be 1540° C. From a certain point of the chequer work zone in which a temperature of the heating gas of about 900° C. prevails, a regulable quantity of hot heating gases is drawn off. The quantity of the hot heating gases which is removed at this point from the heater may have a ratio of 1:2 to 1:3 to the total quantity of the heating gases entering the 900° C. zone. The exact quantity depends upon the construction of the gas heater, the losses in temperature, the kind of refractory material used and other factors.

With the described method of operation the waste gas temperature rise may be held down to a temperature of from 150° C. to 300° C. and therefore remains far below the maximum which is permissible for the cast iron grate (about 400°).

It may be mentioned that the temperature of the waste gases leaving the gas heater would rise from 150° to 600° during the heating period in case the total quantity of the heating gases should be made to pass entirely through the gas heater without part of the gases being withdrawn from

the chequer work zone of increased temperature, as shown in the preceding description of a preferred embodiment of the invention.

A further object of the invention is to provide useful improvements in the method described above in order to utilize the sensible heat of the waste gases leaving the gas heater with a comparatively high temperature, and thus to increase the thermal efficiency of our process.

The solution of this problem according to our invention consists in mixing the heating gases of a comparatively high temperature, that are drawn off from the gas heater, and which have not yet given off entirely their useful heat to the chequer work of the gas heater, which they are not allowed to do because the grate would be stressed too much, completely or partly with cold heating media and advantageously with cold combustion air so that this mixture is used again for heating the regenerative gas heater where the reaction takes place. Under certain circumstances it is advantageous to provide for a further preheating of the hot mixture resulting from the mixture of hot combustion gases and cold heating media by means of a special gas heater, preferably regenerative gas heater, in order to arrive at the high temperatures which will ensure a high efficiency when carrying out the endothermic gas reactions.

The application of this feature of our invention offers the advantage that one can use a considerable amount of the existing heating gases within the process without extending the plant by means of special, more or less intricate, heat producer plants, such as recuperators, steam boilers or the like.

With the above and other objects and features of my present invention in view we shall now describe a preferred embodiment of our invention on the lines of the accompanying drawing.

On the drawing, a suitable installation for carrying out the invention is shown schematically in Fig. 1, and Fig. 2 likewise shows the grate.

The regenerative gas heater, constructed as a hot blast stove of the system Cowper, in which the endothermic gas reactions take place, is marked 1 on the drawing. From the dome 2 of the heater 1 a pipe 3 leads to the dome 4 of a combustion shaft 5 arranged beside the heater. The heating media serving for heating up the chequer work in the gas heater 1 are led into the combustion shaft 5 where they are burnt. Heating gas may for instance be introduced through the pipe 6 at the bottom of the combustion shaft 5. The combustion air necessary for the combustion of the heating gas is preheated in a small regenerator 7 which is connected with the combustion shaft by a pipe 8.

The air regenerator 7 has an air admission pipe 10 which joins the regenerator 7 at the bottom and which is controlled by a valve 9. The pipe 10 is in connection with a fan 11. The suction side of the fan 11 is, on the one hand, connected with a controllable air inlet 13 equipped with a throttle valve 14 by means of the pipe 12 and, on the other hand, with an outlet 16 governed by a shut-off means 15, which is arranged to communicate with the gas heater 1 at a certain height above the gas heater bottom in such a way that waste gases of a certain temperature may be drawn off from the gas heater.

The lower end of the gas heater 1 is, on the one hand, in connection with the stack flue 19 through the pipe 18 controlled by a valve 17 and,

on the other hand, with a pipe 20 which is governed by a valve 21.

The pipe 20 serves for the introduction of the reaction gases or gas mixtures which are to be treated in the gas heater 1.

It may be assumed that the gas heater 1 has been heated up to a desired high temperature, in one operation period, by means of the combustion of gas and air and the passing of the hot combustion gases through the chequer work. After the chequer work is heated up the valve 9 is closed, as well as the pipe 6 through which the gas passes to the combustion shaft 5, and regenerator 1 is shut-off from passing air. Then the valve 21 is opened so that the reaction gas or the reaction gas-steam mixture flows from the pipe 20 into the inside of the gas heater 1, packed with refractory chequer work, whereby a previous flushing of the heater can take place if necessary.

The reaction gases ascending in the gas heater 1 are heated up and react. The reaction products flow through the pipe 3 to the combustion shaft 5, and from there through the pipe 8 and the regenerator 1, and finally escape at the lower end of the regenerator 1 through a pipe 23 controlled by a valve 22.

The heat still existing in the reaction gases can be utilized in a steam boiler 24 from which a pipe 25 leads to a blower 26 to which is connected a washer 27. The cooled and purified reaction gases may then be drawn off at 28 for further use.

As soon as the temperature in the gas heater 1 has dropped under the permissible degree, the admission of reaction gas through pipe 20 is interrupted by shutting the valve 21. Then the shut-off valve 22 for the regenerator 1 is closed and the valves 9 and 15 as well as the pipe 6 are opened. The fan 11 sucks air through 13 and drives it into the regenerator 1 which has been heated up in the previous operation period by hot reaction product gases. In the combustion shaft 5 the hot air meets the fuel gas from the pipe 6. The combustion is practically finished in the combustion shaft 5, in the dome 4 and in the connecting pipe 3 so that only burnt out gases flow into the gas heater 1.

The hot gases give their heat off to the chequer work of the gas heater 1 as they go downwards. A part of the descending gases is sucked through the outlet 16 and the valve 15 by the fan 11 and driven into the regenerator 1 together with the air sucked in through 13. The gases leaving the outlet 16 may have a temperature of 700 to 900° C. Then the cold air entering through 13 will probably be preheated to about 250 to 300° C. by the hot waste gas. The fan 11 has of course to be of such design as to withstand such temperatures.

The rest of the waste gases continue to flow on through the gas heater to the open valve 17 and to the pipe 18 and finally escapes into the stack flue 19.

The following operation period of the plant corresponds to the one which was described at first.

As the fuel gas to be introduced through pipe 6, rich gas (for instance coal distillation gas) or lean gas (for instance producer gas) may be used. In the case of rich gas, the admixing of flue gas to the combustion air is of advantage as the combustion is somewhat delayed and an undue superheating of the refractory lining near the burner is avoided. If, for the heating up of

the gas heater, lean gas is used, the gas may be preheated; it is also possible to mix the lean gas to be preheated with hot heating gases.

At the beginning of the heating period the temperature of the gases leaving the outlet 16 is very low according to the invention. The temperature rises however, in accordance with the heating up of the reaction zone to a considerable extent. If necessary the quantity of hot waste gases added to the air is gradually increased during the heating period by opening valve 15 still more. As the temperature gradually drops down in the regenerator 1, during the heating period, one can compensate the loss by increasing the admixture of hot heating gases from 16 to the air. The loss in temperature results from the application of the regenerative principle for preheating gaseous media.

We have now described our present invention on the lines of a preferred embodiment thereof but our invention is not limited in all its aspects to the mode of carrying it out as described and shown, since the invention may be variously embodied within the scope of the following claims.

We claim:

1. A method of carrying out endothermic gas reactions at high temperature in a tower-like regenerator having a checkerwork filler which comprises: heating the gas to be reacted to the reaction temperature by passing the gas upwardly through the checkerwork filler from the bottom to the top of the regenerator tower; preheating the gas in the lower part of the filler and subjecting the gas to endothermic reaction in the upper part of the filler; drawing the gaseous reaction products off from the top of the regenerator and flowing them through an external combustion zone; then reheating the regenerator checkerwork filler by passing hot combustion gases from the external combustion zone into contact with the filler in the regenerator downwardly therethrough; reheating the endothermic reaction zone of the filler in the upper part of the regenerator to a higher temperature than the preheating zone of the filler in the lower part of the regenerator by passing the full quantity of combustion gases from said combustion zone in a stream through the endothermic reaction zone of the filler in the upper part of the regenerator; reheating the preheating zone of the filler in the lower part of the regenerator to a lower temperature than the endothermic reaction zone in the upper part by withdrawing at an intermediate part of the filler a substantial portion of the stream of combustion gases from the regenerator and passing the remaining portion of the stream of combustion gases on through the lower preheating zone in amount controlled to reheat the same to the lower temperature without overheating the lower preheating zone; mixing the combustion gases withdrawn at the intermediate part with relatively cold combustion media for the external combustion zone; passing the mixture into the combustion zone during combustion therein and mixing the same with extraneous fuel therein.

2. A method of carrying out endothermic gas reactions at high temperature in a tower-like regenerator having a checkerwork filler which comprises: heating the gas to be reacted to the reaction temperature by passing the gas upwardly through the checkerwork filler from the bottom to the top of the regenerator tower; preheating the gas in the lower part of the filler and subjecting the gas to endothermic reaction

in the upper part of the filler; drawing the gaseous reaction products off from the top of the regenerator and flowing them through an external combustion zone and through the checkerwork filler of an external regenerator for pre-heating combustion media; then reheating the regenerator checkerwork filler by passing hot combustion gases from the external combustion zone into contact with the filler in the regenerator downwardly therethrough; reheating the 10 endothermic reaction zone of the filler in the upper part of the regenerator to a higher temperature than the preheating zone of the filler in the lower part of the regenerator by passing the full quantity of combustion gases from said 15 combustion zone in a stream through the endothermic reaction zone of the filler in the upper part of the regenerator; reheating the preheating zone of the filler in the lower part of the regenerator to a lower temperature than the 20 endothermic reaction zone in the upper part by withdrawing at an intermediate part of the filler a substantial portion of the stream of combustion gases from the regenerator and passing the remaining portion of the stream of combustion 25 gases on through the lower preheating zone in amount controlled to reheat the same to the lower temperature without overheating the lower preheating zone; mixing the combustion gases withdrawn at the intermediate part with relatively cold combustion media for the external 30 combustion zone; and passing the mixture of combustion media and combustion gases withdrawn at the intermediate part through said external regenerator to further heat the mixture with the heat recovered from the gaseous reaction 35 products before the mixture enters the external combustion zone, and thence passing said mixture to said combustion zone and mixing the same with extraneous fuel therein.

3. A method of carrying out endothermic gas reactions at high temperature in a tower-like regenerator having a checkerwork filler which comprises: heating the gas to be reacted to the reaction temperature by passing the gas upwardly through the checkerwork filler from the bottom to the top of the regenerator tower; pre-heating the gas in the lower part of the filler and subjecting the gas to endothermic reaction in the upper part of the filler; drawing the gaseous reaction products off from the top of the 40

regenerator and flowing them through an external combustion zone and through the checkerwork filler of an external regenerator for pre-heating combustion media; then reheating the regenerator checkerwork filler by passing hot combustion gases from the external combustion zone into contact with the filler in the regenerator downwardly therethrough; reheating the 5 endothermic reaction zone of the filler in the upper part of the regenerator to a higher temperature than the preheating zone of the filler in the lower part of the regenerator by passing the full quantity of combustion gases from said 10 combustion zone in a stream through the endothermic reaction zone of the filler in the upper part of the regenerator; reheating the preheating zone of the filler in the lower part of the regenerator to a lower temperature than the endothermic reaction zone in the upper part by 15 withdrawing at an intermediate part of the filler a substantial portion of the stream of combustion gases from the regenerator and passing the remaining portion of the stream of combustion gases on through the lower preheating zone in amount controlled to reheat the same to the lower temperature without overheating the lower preheating zone; mixing the combustion gases withdrawn at the intermediate part with relatively cold combustion media for the external 20 combustion zone; passing the mixture of combustion media and combustion gases withdrawn at the intermediate part through said external regenerator to further heat the mixture with the heat recovered from the gaseous reaction products before the mixture enters the external combustion zone, and thence passing said mixture to said combustion zone and mixing the same with extraneous fuel therein; and gradually increasing the amount of the combustion gas that is withdrawn at the intermediate part and mixed with the combustion media to be preheated for combustion as the reheating period progresses and the temperature rises in the upper endothermic reaction zone of the filler in the upper part of the regenerator for the gas reaction, to compensate the temperature drop in the regenerator for further heating the combustion media for the combustion zone.
